Application September 20, 1952, Serial No. 310,717

8 Claims. (Cl. 147—4)

This invention relates to an improvement in method and apparatus for forming slack barrels and deals particularly with a means of simplifying the barrel producing operation.

The production of slack barrels usually requires considerable equipment and a crew of substantial size if all of the operations are to take place simultaneously. If but a small number of barrels is required this may be done by a small crew using but one machine at a time; but as there are several pieces of equipment normally required in the forming operation, this means that a substantial investment must be made for a relatively small return. Slack barrels are of such dimensions that shipment by freight or truck for long distances is uneconomical. It is a primary object of the present invention to provide a method of producing slack barrels which can be economically carried on by a single operator if necessary without the usual loss of economy.

Slack barrels normally require several steps during the assembly process. The staves are usually cut longitudinally to form the proper bulge at the center of the barrel. The staves are then assembled in a setting up and windlassing machine. In this machine the lower ends of the staves are arranged in a circular groove, and a cable is placed to encircle the upper ends of the staves. This cable is tightened in a loop, drawing in all of the staves equally until the edges of the staves are in edge abutting relation throughout their length. A temporary retaining ring is placed about each end of the barrel, completing the operation upon the setting up and windlassing machine.

The barrel is next delivered to a trussing machine. Two wire hoops are usually placed to encircle a barrel at a point spaced from the ends thereof and the trussing machine forces these wire hoops into the proper position to further hold the barrel in its assembled form.

The trussed barrel is then delivered to a suitable apparatus for crozing the ends of the staves, chamfering the same and howeling them. During this operation the ends of the staves are equalized, the croze or groove for the receiving edge of the barrel head is provided and the ends of the staves are beveled or chamfered to receive the head. The barrels are next delivered to the heading machine which inserts a head in one end of the barrel. A hoop is next applied to at least one end of the barrel and this hoop is driven into position by a hoop driving machine. All of these machines are relatively large and expensive and therefore a considerable investment is normally required to produce slack barrels.

An object of the present invention is to provide a method and apparatus for producing slack barrels with a relatively small investment. As a result the cooperage company can set up small plants in various localities and operate these plants with one or two coopers. Thus the barrels may be economically produced near the point where they are used, reducing the cost of transporting the completed barrels.

An added feature of the present invention resides in

the provision of a simple and effective means of producing slack barrels in a small portion of the time previously required. A minimum of equipment is required for this operation.

5 A feature of the present invention resides in the provision of a slack barrel forming apparatus which employs staves which are crozed before the barrel is assembled. Means are provided to expand into the groove or croze at one end of the ring of staves to hold this end of the 10 staves stationary during the windlassing operation or drawing together the upper ends of the staves. A barrel head is applied during the windlassing operation and the hoops may also be applied while the barrel is in this form. At the completion of this operation it is only necessary to apply a final hoop or wire about the barrel near its lower end in order to complete the barrel.

These and other objects and novel features of the present invention will be more clearly and fully set forth in the following specification and claims.

In the drawings forming a part of the specification: Figure 1 is a perspective view of the barrel forming apparatus showing in general the construction thereof.

Figure 2 is a perspective view similar to Figure 1 showing the barrel partially formed.

20 Figure 3 is a top plan view of the apparatus for holding and regulating the position of the staves, the top guard plate being omitted to clarify the illustration.

Figure 4 is a sectional view through the apparatus shown in Figure 3, the position of the section being indicated by the line 4—4 of Figure 3.

Figure 5 is a side elevational view of a portion of the apparatus, certain of the parts being broken away.

Figure 6 is a top plan view of the base upon which the barrel is assembled.

30 Figure 7 is a top plan view of the bottom portion of the base illustrated in Figure 6.

Figure 8 is a perspective view of the finished barrel.

Figure 9 is a perspective view of a stave used in the formation of the barrel illustrated in Figure 8.

40 Figure 10 is a sectional view through the barrel showing the head in place therein.

Figure 11 is a plan view of a modified form of slack barrel forming apparatus.

Figure 12 is a sectional view on the line 12—12 of Figure 11.

45 Figure 13 is a sectional view on the line 13—13 of Figure 11.

In the past it has been common practice to produce slack barrels from slats of wood cut to random widths and then cut to provide outwardly bowed opposite sides.

50 It has been found that the staves can be economically crozed and chamfered before these operations take place. For example, the slats may be milled out at the ends with milling cutters to produce the desired groove and bevel at each end of the board. These operations may 55 take place before the board is cut into rounded form if desired.

Accordingly in forming the barrels, staves of the type illustrated in Figure 9 are employed. Each stave is provided with longitudinally rounded side edges 10 and 11

60 which make the body of the stave 12 wider at its center point intermediate its ends. A generally V-shaped groove or croze 13 is cut into each end of the stave and the stave ends are chamfered or beveled as indicated at 14. These last operations which normally are performed after the barrel has been assembled may be more economically performed while the stave is unassembled.

65 The formation of the barrel is effected through the use of a modified form of setting up and windlassing machine indicated in general by the letter A. This device incorporates certain features which are well known in the art, but also adds certain additional features which have

not previously been used. The set up machine A includes a base portion indicated in general by the numeral 15 and best illustrated in Figures 6 and 7 of the drawings. This base 15 includes upper and lower parts which are generally similar in shape. Figure 6 illustrates the upper portion 16 of the base resting upon the lower portion 17 best illustrated in Figure 7. While the particular shape and form of the base sections is not important, in the particular construction illustrated, the top section 16 of the base comprises a T shaped structure including a forwardly and rearwardly extending elongated strip 19 secured at one end to the center of a transversely extending elongated base portion 20. A pair of parallel bearing portions 21 and 22 are provided at opposite ends of the transversely extending member 20. Brace arms 23 and 24 extend diagonally from the bearing portions 21 and 22 to the elongated base portion 19. A bearing portion 25 is also provided at the end of the base portion 19 opposite that connected to the cross member 20.

The bottom frame portion 17 is virtually identical with the frame portion 16. The portion 19 includes an elongated base portion 26 which is connected at one end to the center of a transverse base member 27. Bearing portions 29 and 30 are secured in parallel relation at opposite ends of the transverse member 27 and brace arms 31 and 32 extend from the bearing portions 29 and 30 to the base portion 26. A bearing portion 33 is provided on the end of the base member 26 opposite the end connected to the transverse member 27.

As best illustrated in Figure 7 of the drawings, the bearing portions 29, 30 and 33 are provided with elongated parallel grooves 34, 35, and 36 respectively. These grooves are designed to accommodate a ball bearing, the ball bearings being illustrated at 37, 39 and 40. The bearing portions 21, 22 and 25 of the upper frame portion 16 are also provided with elongated grooves 41, 42 and 43. The grooves are slightly less than semi-circular in section so that the bearings extend between the two sections of the base and permit relative longitudinal movement in a direction parallel to the axes of the various grooves. A bolt 44 extends through a slot 45 in the upper frame member 16 and into the lower frame member 17 to hold the two base portions assembled and to limit the longitudinal movement of the upper section relative to the lower section.

Anchoring flanges 46, 47 and 49 are provided upon the lower frame member 17 to accommodate anchoring bolts extending into the floor or foundation. The upper frame member 16 is provided with upwardly extending lugs 50, 51 and 52 which are designed to extend into a portion of the movable portion of the setting up apparatus to connect the base thereto.

A generally ring shaped frame 53 is secured to the upper section 16 of the base for movement in conjunction therewith. A spacing ring 54 overlies the frame 53 and is secured thereto. A peripheral ring 55 is also secured to the frame to extend upwardly therefrom in spaced relation to the outer circumference of the ring 54. The spacing between the rings 54 and 55 is sufficient to accommodate the lower ends of the staves 12.

With reference now to Figure 3 of the drawings, it will be noted that four quadrant plates 56 are slidably supported upon the ring 54. Each quadrant plate is provided with a pair of aligned radially extending slots 57 extending therethrough. The slots 57 are positioned at an angle of forty-five degrees from the marginal edges 59 and 60 of the individual quadrants. Bolts 61 extend through the slots 57 and through the ring shaped plate 54 and are threaded into the frame 53. The bolts 61 are not tightened against the quadrants 56 so that these quadrants are movable radially throughout the length of the slots 57.

A circular relatively thick disc 62 is provided with a peripheral flange 63 near its upper extremity. This disc 62 extends through an axial aperture 64 in the ring 54 and the flange 63 engages over the edge of the ring for

support thereby. A series of links 65 are pivotally connected at 66 to the disc 62 the pivots 66 being spaced ninety degrees apart. The links 65 are of equal length and are pivotally connected at 67 to a corresponding quadrant 56. These links 65 are normally angularly related relative to a radial line from the center of the disc 62. Upon rotation of the disc 62 in a clockwise direction as viewed in Figure 1, the quadrants 56 are urged outwardly. Upon rotation of the disc 62 in the opposite direction, the quadrants 56 are drawn inwardly. Thus the outer periphery formed by the quadrants may be increased or decreased by operation of the disc 62.

In order to rotate this disc 62 an arm 69 is connected to the undersurface of the disc to rotate in unison therewith. The arm 69 is connected by a clevis 70 to a piston rod 71 of a piston within the cylinder 72. The piston connected to the piston rod 71 may be actuated by air pressure or by hydraulic pressure to urge the piston rod 71 either into or out of the cylinder 72 and to thereby pivot the disc 62 about its axis a distance sufficient to expand or contract the circle created by the quadrants 56.

As indicated in Figure 4 of the drawings, the quadrants 56 are provided with wedge shaped outer peripheries as indicated at 73. As also illustrated in this figure, the quadrants 56 act upon outward movement to engage into the groove or croze 13 at the lower end of each stave. Thus the staves are not only held in proper relation but are also properly aligned longitudinally by the expanding quadrants as the wedge shaped end of each quadrant will engage in the croze of the staves which it contacts and will move the staves into proper relation so that the croze is continuous when the barrel is completed.

As indicated in Figure 3 of the drawings each side edge 60 of a quadrant 56 is notched as indicated at 74 to accommodate a bushing 75 having a projecting pin of smaller diameter extending upwardly from the center thereof as indicated at 76. A guard plate 77 is provided with angularly spaced apertures to fit upon the bushings 74, the pins 75 extending through suitable apertures in the guard plate. This plate is illustrated in Figures 1 and 4 of the drawings and serves merely to cover the operating mechanism and to act as an additional guide in the stave assembly operation.

With reference now to Figures 1 and 5 of the drawings, a pair of upwardly extending standards 79 are provided in angularly spaced relation from the frame 53. Brackets 80 are adjustably supported by the standards 79 and are secured thereto by clamping bolts 81. The brackets 80 support a guard ring 82 to serve as a guide in aligning the barrel staves. Outwardly inclining fingers 83 are mounted upon the ring 82 to assist in guiding a barrel encircling hoop into proper position to encircle the barrel as it is formed.

The windlassing machine is indicated at B in Figures 1 and 2 of the drawings, this device being generally conventional in form. The windlassing device includes a cable 85 which is designed to encircle the upper ends of the staves when assembled in order to draw them together in the formation of the barrel. The windlassing machine includes suitable pulley guides and a means of drawing the cable loop 85 tightly about the barrel. As the detail construction of this device is well known in the art, the structure is not shown in detail.

A barrel heading device is supported closely adjacent to the setting up and windlassing apparatus. This device includes a suction fan 86 which is driven by a motor 87 or by any other suitable source of power and an elbow 89 connected to the intake of the suction fan 86. The elbow 89 is connected by a vertical tubular conduit 90 to a laterally extending arm 91 which is connected to the vertical tubular member 90 by a swivel connection 93. A suction plate 92 is connected to the laterally extending member 91 through a suitable elbow 94. The suction plate 92 is circular in form and is designed to pick up

a circular barrel head 95 and to properly position it within the barrel being formed.

The barrel heading apparatus C also includes a cylindrical hopper 96 for accommodating a series of barrel heads 95 in superimposed relation. A recessed slide 97 is slidable beneath the hopper 96 and the lowermost barrel head of the series may drop into the receiving recess in the slide 97. By moving the slide 97 laterally the lowermost barrel head is moved from beneath the hopper 96 into position where it may be picked up by the suction plate 92.

In carrying out the method and in operating the apparatus the following steps are taken. First a temporary hoop is inserted into the retaining ring 82 to serve temporarily as a means of holding the lower end of the barrel in proper form when removed from the setting up and windlassing machine. The staves 12 are assembled in the setting up machine, the lower ends of the staves being inserted between the ring 54 and the ring 55. Staves of the proper width are provided so that the ring of staves is continuous between these rings 54 and 55.

The windlassing cable 85 then encircles the keg. The cable is lifted so as to encircle the barrel near the upper extremity thereof and a suitable foot control 99 is actuated which causes the windlassing coil to tighten about the barrel staves, gradually drawing them together at their upper ends. As the circumference of the loop decreases the upper base portion 16 and the mechanism supported thereby is gradually moved rearwardly so that the direct pull upon the cable may compress the upper ends of the staves together.

When the staves are almost in edge abutting relation the heading machine C is actuated. The suction plate 92 picks up a barrel head 95 from a recess in the slide 97 and this head is swung into position within the barrel. The tightening operation is continued until the wedge shaped marginal edge 100 of the barrel head engages in the chimes 13 of the assembled hoops.

While still retaining the windlassing coil in position a hoop is placed about the upper end of the barrel to hold the staves in their proper position. The windlass coil is then loosened and swung from around the barrel. The barrel is then removed and is virtually complete.

Wire trusses 101 and 102 are placed about the barrel and a similar truss 103 is placed about the barrel near the open lower end thereof before the temporary hoop is removed. When the trusses and hoops have been driven into position and fastened in place the barrel is complete.

Thus it will be seen that in producing barrels by the present method only two machines are required in place of the numerous machines previously required. The staves are furnished ready for use and can be easily changed without a resulting loss of economy. Before completion the staves are grooved and chamfered in the manner illustrated in Figure 9 of the drawings.

In the past it has been impractical to insert the head of a barrel in place during the setting up operation as the staves had not been crozed and chamfered at this stage of the assembly. With the present method the heading apparatus comprises a part of the assembly or setting up operation and the windlass in tightening the staves also secures the barrel head in place. This eliminates the requirement for a header for inserting the heads into the barrels after the crozing and chamfering operation. No force is required to press the head in place as the head may be held in proper location while the staves are tightened about the same. Thus one machine previously required in the production of slack barrels may be eliminated. As the staves may be milled out into the proper end shape before the formation of the stave if desired, the requirement for an expensive crozing machine is eliminated and the requirement for a chamfering and howeling machine is eliminated. While a

somewhat different apparatus is employed to cut the grooves and to bevel the stave ends, this mechanism is relatively simple and inexpensive as compared to a regular slack barrel crozing machine or a regular slack barrel chamfering and howeling machine.

By preforming the staves with the croze and bevel thereupon previous to the erection of the barrel, the staves and heads may be furnished the cooper and the barrel may then be completed with the use only of the apparatus illustrated and a hoop driving or trussing apparatus. Both machines can be readily operated by a single man. The operator may first assemble the barrel with the apparatus illustrated and later apply the remaining hoops and trusses, or if two coopers are working, one can operate each apparatus. As a result slack barrels may be erected near the point of final use without the outlay of a considerable investment for equipment, thus saving most of the transportation charges.

In Figures 11, 12 and 13 is disclosed a modified form of slack barrel setting up machines. This apparatus, indicated in general by the letter D, incorporates a stave assembly apparatus, a windlassing apparatus (not illustrated in the drawings, but identical to that previously described) and a barrel head supporting device.

The apparatus D includes a frame plate 104 having two pair of opposed parallel angle brackets 105 secured thereto. A track member 106 is mounted on the floor outwardly of each pair of angle brackets 105. Each track member includes a base flange 107, an upright flange 109, and a horizontal inwardly extending flange 110. A pair of vertically spaced bearing rollers 111 are pivotally supported on horizontal pivots 112 to engage above and below the horizontal flanges 110 of the tracks 106. The frame plate 104 is thus slidably supported for limited horizontal movement upon the tracks 106. As a result the barrel may be moved during its assembly to maintain the windlassing cable ends in proper position.

A ring shaped disc 113 is mounted on the plate 104. This disc has its outer diameter the approximate internal diameter of a barrel end. A ring 114 is supported on the base plate 104 in spaced relation to the periphery of the disc 113. The space between the disc 113 and the ring 114 forms a groove into which the lower ends of staves 12 are inserted at the start of the slack barrel assembling operation.

A series of sector shaped quadrant plates 115 are supported on the disc 113. Radially extending slots 116 are provided in each plate 115 and bolts 117 extend through the slots 116 to limit the radial movement of the plates. The plates 115 have a wedge shaped edge 119 designed to engage in the croze of the staves 12 and to hold the grooves of the various staves in a common plane.

A rotatable thick disc 120 extends through an axial opening in the disc 113 and the plate 104. A flange 121 at the top of the disc 120 overlies the disc 113 and holds the disc in place. Links 122 are pivoted to each quadrant plate 115 at 123 and pivoted to the disc 120 at 124. Rotation of the disc 120 moves the links toward or away from radial position, moving the quadrant plates 115 outwardly or inwardly.

An arm 125 is secured to the disc 120 to rotate the same. A fluid cylinder 126 is hinged at 127 to the plate 104 and has a piston rod 129 projecting from its opposite end. The piston rod is provided with a bifurcated end 130 hinged at 131 to the arm 125. The cylinder includes a piston 132 connected to the piston rod 129. This piston may be reciprocated by air or hydraulic fluid to rotate the disc 120 and to expand the quadrant plates 115 outwardly to clamp the staves 12 against the frame ring 114.

A bracket 133 is secured to the under surface of the frame plate 104. The bracket 133 is provided with a downwardly off-set center portion 134 best seen in

Figure 13. The bracket portion 134 is provided with a circular aperture 135 therethrough axially aligned with the disc 120. An elongated vertical cylinder 136 extends through the bracket aperture and depends downwardly therefrom. A piston 137 in the cylinder 136 is provided with a piston rod 139 which extends upwardly through an aperture 140 in the disc 120. A disc 141 is mounted at the upper end of the rod 139. As shown in Figure 13, a pair of guide rods 142 are connected to the disc 141 and extend through bearing openings 143 in the frame plate 104. The rods 142 extend through notches 144 in certain of the quadrant plates 115. The notches 144 are of sufficient size to permit expansion of the circle formed by the outer edges of these plates 115.

The disc 141 is of slightly smaller diameter than the barrel ends and is designed to support a barrel head 145. Thus when desired the head may be supported in proper relation to the barrel by the disc 141.

In operation the staves 12 are assembled in the circular groove between the disc 113 and the ring 114. The edges of the lower ends of the staves are in abutting relation. A temporary retaining hoop 146 is supported to encircle the staves near the lower end thereof. When the staves have been assembled the windlassing loop is placed to encircle the upper ends of the staves. This windlassing loop is gradually tightened, the staves being bent inwardly as the edges of the staves abut one another. The shape of the staves acts to form the bulge at the center of the barrel.

Before the upper ends of the staves are in edge abutting relation the cylinder 136 is actuated by air or hydraulic fluid to raise the piston 137 and accordingly to raise the piston rod 139 and the disc 141. The cylinder is of proper size to elevate the disc so that it is in proper relation to the crozes at the upper ends of the staves. The barrel head 145 is then placed upon the disc 144 and the windlassing operation is completed, drawing the staves tightly about the barrel head 145. The end hoop 147 is then placed about the end of the barrel to retain the staves in proper relation. The windlassing cable is then loosened and removed and the barrel is ready to be trussed with suitable wire rings or hoops.

As indicated in Figure 13 of the drawings, an elongated aperture 149 is provided in the floor between the tracks 106 so as to permit movement of the cylinder 136 and the arms 142 in lowered position thereof. After the head has been put into place the air or hydraulic fluid in the cylinder 136 is reversed so as to lower the disc 141 to simplify the task of removing the assembled barrel.

In the foregoing description it has been indicated that the head supporting disc is raised after the barrel is partially formed. Obviously the disc may be raised before the start of the windlassing operation if desired so as not to interrupt the operation. The structure illustrated and described takes the place of the heading machine C illustrated in conjunction with the barrel set up machine A. The disc forms a positive means of supporting the head and requires less space than the heading machine previously described.

In accordance with the patent statutes, the principles of construction and operation of the method and apparatus for forming slack barrels have been described, and while it has been endeavored to set forth the best embodiment thereof, it is desired to have it understood that these are only illustrative thereof and that obvious changes may be made within the scope of the following

claims without departing from the spirit of the present invention.

I claim:

1. A slack barrel setting up device for use in conjunction with staves having crozed grooves at at least one end thereof, the device comprising a frame, a stave support including a base having a ring shaped groove in the upper surface thereof designed to accommodate the grooved ends of the staves, a generally cylindrical wall forming the outer side of said groove and a plurality of outwardly movable clamping plates supported by said base and spaced inwardly of said wall, and means for moving said plates outwardly toward said wall and into the crozed grooves on said staves, clamping said staves against said wall.

2. The structure described in claim 1 and in which said clamping plates are radially movable relative to the axis of said ring shaped groove.

3. The structure described in claim 1 and in which said clamping plates are sector shaped.

4. The structure described in claim 1 and in which the means for moving said clamping plates outwardly comprises a pivotal member supported at the axis of said ring shaped groove, and links pivotally connecting said pivotal member and said clamping plates to move the clamping plates outwardly upon rotation of the pivotal member in one direction.

5. A device for making barrels from pre-crozed staves comprising a base upon which the ends of the staves may rest, a spacing plate overlying the base having a circular periphery, a ring concentrically spaced from said plate to form an annular groove for receiving the end portions of the staves extending beyond their respective crozes, said ring extending upwardly to at least the height of the crozes, and expandable means inwardly of said ring and expandable toward said ring for engagement into the croze of each stave to urge said end portions of the staves outwardly against said ring for positively holding each stave in a predetermined relation to the others.

6. The structure described in claim 5 in which said expandable means includes a plurality of radially movable segmental plates having wedge-shaped arcuate edges substantially complementary with said crozes and engageable therewith.

7. A barrel making device including a base upon which the ends of staves may rest, a generally cylindrical wall extending upwardly from said base, clamping means on said base spaced inwardly of said wall, said wall and clamping means being spaced sufficiently to accommodate previously crozed staves standing on one end therebetween, and means for moving said clamping means outwardly toward said wall, said clamping means extending into the crozes at said one end of the staves and clamping said staves against said wall.

8. The structure described in claim 7 and including means engageable with the staves intermediate the ends thereof for drawing the other ends of the staves together.
